Primary Examiner — Mark A Goodwin(74) *Attorney, Agent, or Firm* — Kirk A. Buhler; Buhler & Associates Patenting(57) **CLAIM**

The ornamental design for a shade frame for a boom lift, as shown and described.

DESCRIPTION

FIG. 1 is a bottom perspective view of a shade frame for a boom lift;

FIG. 2 is a left side elevation view, the right side elevation view being a mirror image thereof, and

FIG. 3 is a front elevation view thereof;

FIG. 4 is a rear elevation view thereof;

FIG. 5 is a top plan view thereof;

FIG. 6 is a bottom view thereof;

FIG. 7 is a top perspective view showing my new design in its environment; and,

FIG. 8 is a bottom perspective view with the top portion of the frame rotated.

The broken lines in FIG. 7 depict environmental subject matter for illustrative purposes only and form no part of the claimed design.

1 Claim, 8 Drawing Sheets(56)
